US0D1061756S

(12) **United States Design Patent** (10) **Patent No.:** **US D1,061,756 S**
(45) **Date of Patent:** **** Feb. 11, 2025**

(54) **BARBELL**

(71) Applicant: **Coulter Ventures, LLC.**, Columbus, OH (US)

(72) Inventor: **Martin Pritchett**, Columbus, OH (US)

(73) Assignee: **Coulter Ventures, LLC.**, Columbus, OH (US)

(**) Term: **15 Years**

(21) Appl. No.: **29/843,969**

(22) Filed: **Jun. 24, 2022**

(51) LOC (15) Cl. **21-02**

(52) U.S. Cl.

USPC **D21/681**; D21/679; D21/682

(58) **Field of Classification Search**

USPC D21/679, 680, 681, 682, 694; 482/104, 482/106

CPC A63B 21/0724; A63B 21/0728; A63B 21/072

See application file for complete search history.

(57) **CLAIM**

The ornamental design for a barbell as shown and described.

DESCRIPTION

FIG. 1 is a top, front, right perspective view of a barbell showing my new design;

FIG. 2 is a bottom, rear, left perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines immediately adjacent to the shaded area define the bounds of the claimed design and form no part thereof. The broken lines depicting the remainder of the barbell show features that form no part of the claimed design.

1 Claim, 8 Drawing Sheets
